US00D852153S

(12) **United States Design Patent** (10) **Patent No.:** **US D852,153 S**
(45) **Date of Patent:** **** Jun. 25, 2019**

(54) **TELEVISION APPARATUS**

(71) Applicant: **LG ELECTRONICS INC.**, Seoul (KR)

(72) Inventors: **Huisik Kim**, Seoul (KR); **Hodong Hwang**, Seoul (KR)

(73) Assignee: **LG ELECTRONICS INC.**, Seoul (KR)

(**) Term: **15 Years**

(21) Appl. No.: **35/503,810**

(22) Filed: **Apr. 12, 2017**

(80) **Hague Agreement Data**

Int. Filing Date: **Apr. 12, 2017**

Int. Reg. No.: **DM/095746**

Int. Reg. Date: **Apr. 12, 2017**

Int. Reg. Pub. Date: **Oct. 13, 2017**

(30) **Foreign Application Priority Data**

Oct. 18, 2016 (KR) 30-2016-0049931

(51) **LOC (11) Cl.** **14-03**

(52) **U.S. Cl.**

USPC **D14/126**

(58) **Field of Classification Search**

USPC D14/125-134, 239, 314-316, 322, 326, D14/334-336, 339-341, 371, 373-374,

D14/448, 450; D21/329, 332, 515

CPC G06F 1/16; G06F 1/1601; G06F 1/1637;

H04N 5/64; H05K 5/0204; H05K 5/0017;

H05K 5/0217

(57) **CLAIM**

The ornamental design for a television apparatus, as shown and described.

DESCRIPTION

1. Television apparatus

1.1 : Perspective

1.2 : Front

1.3 : Back

1.4 : Left

1.5 : Right

1.6 : Top

1.7 : Bottom

1.8 : Enlarged

1.9 : Enlarged

The evenly-spaced broken lines show portions of the article; the smaller unevenly spaced broken lines define the bounds of the claimed design; the larger unevenly spaced broken lines are used to indicate the sections of the views shown enlarged; all broken lines form no part of the claimed design.

1 Claim, 8 Drawing Sheets
